UNITED STATES PATENT OFFICE.

JAMES D. MILLAR, OF MILWAUKEE, WISCONSIN.

ROLLER-MILL.

SPECIFICATION forming part of Letters Patent No. 311,508, dated February 3, 1885.

Application filed April 28, 1884. (No model.)

To all whom it may concern:

Be it known that I, JAMES D. MILLAR, a citizen of the United States, residing at Milwaukee, in the county of Milwaukee and State of Wisconsin, have invented certain new and useful Improvements in Roller-Mills, and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention is explained by reference to the accompanying drawings, in which Figure 1 represents a side view of my improved roller-mill, looking toward the ends of the rolls. Fig. 2 is an end view. Fig. 3 is a vertical section of the hopper, showing the agitators. Fig. 4 is a top view of the hopper. Fig. 5 is an end view of one pair of the grinding-rolls, showing the scraping devices by which the material is prevented from adhering to the surfaces of the rolls. Fig. 6 is a front view of the devices shown in Fig. 5. Fig. 7 represents a side view of the machine with the hopper removed, showing more particularly the arrangement of the belt-pulleys and belts. Fig. 8 represents an end view of Fig. 7. Fig. 9 represents an end view of the devices for attaining both the horizontal and vertical adjustment of the grinding-rolls, one end only of one of each pair of rolls being provided with such adjusting devices. Fig. 10 represents a front and Fig. 11 a top view of Fig. 9. Fig. 12 represents a side view, and Fig. 13 a top view, of the devices for simultaneously closing and opening the throat of the hopper. Fig. 14 represents the belts and belt-pulleys for operating the agitator and feed-rolls. Fig. 15 represents a side and Fig. 16 an end view of the automatically-closing door in its closed position. Fig. 17 represents a side and Fig. 18 a top view of the automatically-closing door open. Figs. 19 and 20 show the position of the driving-belts and the loose pulleys E' and C' on the respective sides of the machine.

Like parts are represented by the same reference-letters throughout the several views.

These improvements mentioned are shown in connection with the so-called "double-roller" mill, or that class of mill in which two pairs of grinding or reducing rolls of like construction and capacity are used in connection with a double hopper and single supporting frame or shell. Most of the improvements shown are, however, as well adapted to be used with the so-called "single-roller" mill, or mill having but a single pair of reducing-rolls, while others are adapted to be used only in the former class, or so-called "double-roller" mills.

A is a substantial cast-metal shell, which serves the twofold purpose of a frame to the mill and a receptacle for the ground material which falls into it from the grinding-rolls, and from which it escapes through an opening in its bottom.

B is the hopper, into which the grain is conducted preparatory to grinding. The hopper B is divided into two compartments by the partitions C, which diverge toward the ends E E.

D D are the feed-throats through which the grain escapes from the hoppers.

F F are adjustable feed-rolls, which are adapted to be so adjusted in the throats as to regulate and govern the escape of grain from the hopper, or entirely stop the grain, thus serving the threefold purpose of stopping the escape of grain, of governing the quantity of grain which escapes, and acting as agitators to prevent the grain from stopping up the throats. The feed-rolls are supported upon the downward-projecting arms G G of the levers S S. The levers S S are pivoted upon the bolts H H. The upward-projecting arms I of the levers S are both connected to the arm J by rods K K, whereby they are both simultaneously operated by the movement of said arm. The arm J is fitted to an eccentric or cam, L, by which it is moved upward and downward in a vertical line as said eccentric is turned. The eccentric L is rigidly affixed to shaft M, which shaft has its support in the sides of the hopper, across which it extends. Upon the opposite end of the shaft M is also provided an eccentric or cam and arm, J, which arm is in like manner connected by rods and

levers with the opposite ends of the feed-rolls, as shown in Fig. 13.

To one end of the shaft M is attached a handle, N, by which said feed-rolls are moved 5 and adjusted. When said handle is thrown toward the right, the arms J upon both sides of the hopper are moved upward by the cams L, whereby the rods K K and arms I I on both sides of the machine are moved upward and 10 outward, and the arms G G and the respective shafts O O of the feed-rolls F F are moved downward and away from the throats of the hopper, thereby permitting the escape of grain. By a reverse movement of said handle 15 said feed-rolls are moved upward and the throats of the hopper closed. The rods K are formed in two parts, which are connected together by the cylindrical nuts T operating on screw-threads. The threads on said nuts and 20 rods are so formed as to cause the parts of said rods to be drawn toward each other by turning said nuts in one direction, and to be separated by turning said nuts in the opposite direction, whereby said rods may be extended 25 or contracted, as may be required, in adjusting the feed-rolls to regulate the escape of grain. The upper ends of the arms J are provided with slots or guideways U, through 30 which project stationary pins V, which pins serve to hold the upper ends of said arms in place and prevent them from turning as they are raised and lowered by the action of the cams or eccentrics L. The shafts O of the feed-rolls are each provided with pulleys P P'. 35 Motion is communicated to said shafts O and feed-rolls through band-pulley Q, belt A', pulley P, pulley C, belt B', and pulley P'. The belt A' is, when released from the action of a belt-tightener, so slack that it ceases to communicate motion to said feed-roll. The belt-tightener consists of pulley D' and arm E'. The arm E' is rigidly affixed to the shaft M, and the tightener-pulley is thrown out of and in contact with the belt A' as the handle N is 40 moved toward the right and left. Thus it is obvious that the same movement of the handle which opens the throats of the hopper throws the band-tightener in contact with the belt and starts the feed-rolls, and that the reverse movement of the handle simultaneously 45 closes the hopper-throats and stops the feed-rolls.

In addition to the eccentrics L, two other eccentrics, F' F', are attached to said shaft M, 55 which are respectively connected by the rods K' K' to the upper ends of the arms G' G'. The arms G' G' are supported at their lower ends upon pivotal bolts H' H', which permit their upper ends to be moved slightly toward the 60 right and left, as required when throwing one of each pair of grinding-rolls I' I' (which are supported thereby) toward and from the other. The eccentrics F' F' project in opposite directions from opposite sides of the shaft M, where- 65 by as the handle is moved the arms G' G' with their rolls are moved in opposite directions to each other. Thus as the handle is thrown to-

ward the right the following three separate objects are attained, viz: The hopper is opened, the feed-rolls are started in their rotary movement, and the grinding-rolls are moved toward each other in position for grinding, and when the handle is thrown toward the left the feed-rolls are thrown up into the throats of the hopper, thereby closing them. The 70 band-tightener is thrown back from the band and the feed-rolls stopped, while the grinding-rolls are separated from each other. The rollers J' are supported at each end in stationary journal-boxes L', and the required 75 adjustment of the rolls to each other for producing the various reductions is attained by moving the rolls I'. In addition, therefore, to the temporary movement given to the rollers I' whenever the mill is stopped by the action 80 of the handle N, a so-called permanent adjustment of the rolls is attained by the hand-screws M' M'. If desirous to have the rolls I' and J' in closer contact, the hand-nuts M' M' are turned toward the left, (reference being 85 had to Fig. 9.) whereby the lever or arm G', with the roll I', are moved toward the roller J'. If desirous to produce a coarser reduction, the roll I' is adjusted toward the right by turning said hand-nuts in the opposite direction. Thus the space between the rolls is 90 easily regulated and the finest adjustment 95 that may be required is readily made.

Between the bearing-surfaces of the inner hand-nuts and the opposite bearings of the 100 arms G' are interposed spiral springs N', which permit said arms G' and rolls I' to move slightly away from the outer or stationary rolls, J', as may be required to permit of hard 105 foreign substances passing between the rolls.

In addition to the horizontal adjustment of the rolls I' described, it is necessary to provide for a vertical adjustment of one end of said rolls I', whereby the point of contact of the peripheries of said rolls I' and J' may be 110 brought to and retained in the same plane. To accomplish this object a movable eccentric journal-box, O', is provided at one end of each of said movable rolls I' for the reception of the shafts P', one of which is shown in Fig. 115 10. The exterior surfaces of the journal-boxes O' are spherical in shape at their centers, as shown in Fig. 10, and are fitted to stationary bearings Q', provided therefor in the arms G'. The openings through said movable journal-boxes O' being formed eccentric thereto, it is obvious that while the peripheries of said movable journal-boxes remain, when turned, upon the same plane the eccentric journal-bearings therein are thrown 120 either above or below the center, or at any intermediate point between the extreme upward and downward movement desired, whereby the ends of the roller-shafts therein are raised or lowered, and thereby adjusted at any de- 125 sired point which may be required to bring the point of contact of the rolls I' upon the same plane with that of the rolls J'.

It is obvious that owing to the spherical

shape of the exterior of the journal-boxes O' they form a universal joint, which permits them to be inclined as well as turned in their bearings, to conform to the inclination of the 5 shaft when adjusting the rolls, and owing to their convex shape they are more readily duplicated and fitted to and retained in their bearings in the supporting-arms.

In making the mill the rolls are arranged as 10 nearly parallel to each other as possible, and the vertical adjustment described becomes necessary only to correct some slight variation of the rolls in this respect as may arise by the wearing of the journal-bearings or the 15 peripheries of the rolls, and it is obvious that to make such correction and bring the rolls parallel to each other it becomes necessary to move but one end of one roll only. When the rolls are thus adjusted parallel to each 20 other, such adjustment remains permanent, while the movable rolls are moved bodily toward and from the other horizontally by the means described without changing the relative distances between their ends. The journal 25 box at the opposite end of said roll-shaft is also spherical in shape, like that shown in section in Fig. 10, and is adapted to turn in its bearings in the supporting-arm to conform to the inclination of the shaft as the eccentric 30 journal-box is turned. The projecting ends of the eccentric journal-boxes O' are made angular, to permit of the application of a wrench or instrument for adjusting them. When ad- 35 justed, the journal-boxes may be rigidly af- fixed at such point by the set-screws R', Fig. 9.

S' is a pulley-shaft, located below the floor, from which motion is communicated by two 40 separate pulleys, T' and W', and belts U' and V', to opposite ends of the machine. The belt U' passes around the pulley T', and from thence up through the floor, diverging toward the right and left, passing over the pulleys A'' and B'', and from thence down around and beneath the flanged loose pulley C', whereby, as 45 said band revolves, it drives one of each pair of grinding-rolls, causing them to rotate in the same direction toward the left, while the other two rolls are driven in the same direction toward the right by the band V', which passes 50 around the pulley W', and from thence between and against the pulleys D'' and E', and around the loose flanged pulley E'', as shown by Fig. 7. Both of the pulley-rims C' and E'' consist in the rim or annulus a' and flanges b', 55 and they are respectively retained in place solely by the respective belts U' and V' against the peripheries of the respective pulleys A'' B'' and D'' E', as shown in Fig. 7, their office being solely to retain said belts against the 60 peripheries of said pulleys, whereby each belt is adapted to rotate one of each pair of rolls in the same direction as a provision against accident.

G'' is an automatically-closing door, which 65 is secured to the case A at its lower edge by hinges d' d', and is adapted to open outwardly. The respective sides of the door

are provided with triangular side flanges or plates, H'', which, when the door is thrown back and open, serve to prevent the flour or 70 ground material which clings to the back of the door from falling to the floor, as it otherwise would, over the respective sides of the door.

To the inward projecting edges of the flanges 75 H'' is attached a weight, I'', by means of the plate J''. The weight I'' is so arranged that when the door is open it still projects within the shell in such a manner that the line of the center of gravity is upon the opposite side of 80 the hinges or pivotal point from that of the door, whereby as soon as the door is released it will be automatically closed by the gravity of said weight.

K'' K'' are reciprocating bars, for agitating 85 the grain or material in the hopper above the feed-rolls, whereby it is caused to flow uniformly therefrom to the feed-rolls. The bars K'' are centrally supported at their sides by the hangers L'', which are rigidly affixed thereto. Holes are formed in the upper ends of the 90 hangers L'' for the reception of the rods M'', from which said hangers and bars are suspended. The rods M'' are rigidly affixed at their ends to the sides of the hopper by nails 95 or screws, as shown. The upper ends of the bars K'' are attached to the oscillating bracket N'' by links O'' O'' and pivotal bolts g' g'. The bracket N'' is centrally supported at its lower 100 end upon pivot P''.

Between the arms h' h' of the bracket is an eccentric, R', mounted upon the shaft S'' and adapted to rotate with it. Thus as the shaft S'' rotates a rocking motion is communicated therefrom through said eccentric to said bracket, and as said bracket rocks on its support it communicates a reciprocating motion to said agitating-bars K''. Motion is communicated to the shaft S'' from the pulley C' through belt T'' and pulley U'', and from thence to said eccentric and the agitating-bars, as mentioned.

The devices for scraping the grinding-rolls (shown in Figs. 5 and 6) are supported at their respective ends, from the sides of the case A, by arms V'' V'', and they consist in the screw-threaded adjustable standards W'' W'', hand-nuts Y'' Y'' and Z'' Z'', spiral springs A''', and plate B'''. The spiral springs support the standards and scraping-plates while they yield sufficiently to conform to any unevenness of 115 the surface of the rolls without breaking the scrapers. The hand-nuts Z'' Z'' limit the upward movement of the standards and plates caused by the springs, and serve in adjusting said plates to the rolls, while the hand-nuts Y'' 120 Y'' serve as bearings to the upper ends of the springs as well as a means of increasing and diminishing the tension of the springs.

Heretofore it has been common in the so-called "double-roller" mills to locate the adjustable roll of each pair upon the outside or at the ends of the machine. By my improvement such adjustable rolls are arranged upon the inside next to each other, by which ar- 130

angement I am enabled to connect them with and simultaneously operate them and the feed-rolls and band-tightener by a single lever, whereby, as said lever is thrown toward the right, the rolls are brought together in position for grinding, the feed-rolls are moved away from the mouths of the hopper, the hopper-throats are opened, the band-tightener is brought against the band, the feed-rolls are caused to rotate, and a reciprocating motion is communicated to the agitating-bars, thereby simultaneously starting all the operative mechanism, while by the reverse movement of said lever all the parts are reversely moved, the flow of grain or material is cut off, and the agitator and feed-rolls are stopped.

The eccentric journal-boxes O' are preferably secured to the arms G' in globe or spherical shaped bearings Q', as shown in Fig. 10, as they are thereby more readily fitted thereto or replaced. Cylindrical or other form of bearings may, however, be used. When the globe-bearings are used, the bearings of the arms G' are made to conform in shape thereto.

Having thus described my invention, what I claim as new, and desire to secure by Letters Patent, is—

1. In a roller-mill, the combination, with one end of each of the shafts of the adjustable rolls, of a spherical-shaped movable journal-box having an eccentric journal-bearing in which the journal of each shaft rotates, said journal-box being adapted to be both inclined and turned in its bearing in the supporting-arms, substantially as and for the purpose specified.

2. In a roller-mill, the combination, with both ends of each of the two central roll-shafts of the spherical-shaped movable journal-boxes O' O', and with one end of each of said shafts, of eccentric journal-bearings in which the journal of each of such shafts rotates, adjustable arms G' G', pivotal supports H' H', and operating mechanism for adjusting the upper ends of the arms H H, substantially as set forth.

3. In a double-roller mill, the combination of shaft M, handle N, eccentrics F' F', screw-rods K' K', arms G' G', each carrying one end of the two central rolls, hand-nuts M' M', springs N' N', and pivotal supports H' H', as set forth.

4. In a double-roller mill, a single driving-belt for simultaneously rotating one of each of two pairs of grinding-rolls in the same direction, in combination with the fixed band-pulleys of such rolls, of a free open pulley-rim interposed partially between and held in contact with said fixed pulleys, a belt passing from the drive-shaft to and partially around and between said fixed pulleys, and nearly around said open pulley-rim and retaining said rim against the belt on the peripheries

of both of said fixed pulleys, whereby said belt is retained in contact with and rotates both 65 of said fixed pulleys in the same direction, as set forth.

5. In a double-roller mill, the combination of pulleys D' and E', respectively attached to one roll of each of two pairs of grinding-rolls, with the open pulley-rim E'', and driving-band V', said driving-band V' being retained in place against said pulleys D' and E' by said pulley-rim E'', band-pulleys A'' and B'', pulley-rim C'', and driving-belt U', where-by the respective rolls in both pairs are rotated by separate bands in opposite directions toward each other, as set forth.

6. The combination, with a case, of a roller-mill and a door hinged at its lower edge to 80 such case and provided with vertical side plates, of a counterpoise rigidly affixed to said side plates within said case upon the opposite side of the center of gravity of said door, whereby it is adapted by its gravity to 85 close said door upwardly, as set forth.

7. The devices for holding the scraping-blades in contact with the grinding-rolls, consisting in the combination, with the respective ends of said blades, of the screw-cut adjustable standards W'' W'', adjusting hand-nuts Y'' and Z'', springs A'' A'', and supporting-arm V'', substantially as set forth.

8. The combination, with the throat or discharge of the hopper of a roller-mill having 95 rigid immovable sides, of an adjustable agitating-roll, movable bearings, and suitable adjusting mechanism therefor by which it is retained in actual close contact with both sides 100 of said throat as the hopper is closed, and removed as the hopper is opened, as set forth.

9. In a roller-mill, the combination of shaft M, handle N, eccentrics L, arm J, screw-rods K K, arms S S, pivotal supports H H, and feed-rolls F F, said feed-rolls being adapted 105 to be both simultaneously adjusted by moving said handle, as set forth.

10. The combination, with the hopper having upwardly-converging bottoms C, and the feed-rolls, of the upwardly-converging vertically-moving agitating-bars K'', the eccentrics at their upper ends, and operative mechanism by which said bars are reciprocated toward and from the feed-rolls, as set forth.

11. The combination of the agitating-bars 115 K'', bracket U'', eccentric R'', shaft S'', band T'', and pulley C', said agitating-bars being connected with said bracket and adapted to move upward and downward as said bracket is rocked, as set forth.

In testimony whereof I affix my signature in presence of two witnesses.

JAMES D. MILLAR.
